FEEDING MECHANISM

Merrill J. Fox, Chicago, Ill., assignor to Bell & Howell Company, Chicago, Ill., a corporation of Illinois Filed Nov. 20, 1957, Ser. No. 697,700 11 Claims. (Cl. 271—57)

This invention relates, generally, to feeding mechanisms and it has particular relation to mechanisms for feeding documents, such as checks, to recording apparatus, for example a microfilm recording device.

Among the objects of this invention are: To provide means for sensing the presence of a document being fed between feed and retard rollers of a feeding mechanism in a new and improved manner; to employ a sensing roller for this purpose and to arrange for it to disconnect the drive to the feed roller on the feeding of a document or documents having more than a predetermined thickness; to automatically regurgitate the document or documents on the stopping of the feed roller; to drive the retard roller continuously and independently of the drive to the feed roller; to mount the sensing roller on a rockably mounted sensing lever; to provide a normally engaged electromagnetically controlled clutch between the feed roller and its driving means and to control the energization of the electromagnetic means by a switch which is controlled by the sensing lever; to manually operate the sensing lever and thereby the switch to stop the feed roller and permit the retard roller to regurgitate a document or documents between it and the feed roller; to bias the sensing lever and thereby the sensing roller toward the feed roller; to adjust the position of the switch relative to the sensing lever in order to vary the document thickness that can be accommodated between the feed and sensing rollers; to mount the retard roller for bodily movement toward and away from the feed roller about an axis spaced from its axis of rotation; and to provide for biasing the retard roller toward the feed roller and for adjusting the biasing action to vary the pressure applied to a document or documents between them.

Other objects of this invention will, in part, be obvious and in part appear hereinafter.

This invention is disclosed in the embodiment thereof shown in the accompanying drawings and it comprises the features of construction, combination of elements and arrangement of parts that will be exemplified in the construction hereinafter set forth and the scope of the application of which will be indicated in the appended claims.

For a more complete understanding of the nature and scope of this invention reference can be had to the following detailed description, taken together with the accompanying drawings, in which:

FIGURE 1 is a top plan view of a feeding mechanism constructed in accordance with this invention, certain parts being broken away in order to show more clearly the details of construction;

FIGURE 2 is a view, in front elevation, of the feeder shown in FIGURE 1;

FIGURE 3 is a vertical sectional view taken generally along the line 3—3 of FIGURE 2;

FIGURE 4 is a horizontal sectional view taken generally along the line 4—4 of FIGURE 3;

FIGURE 5 is a sectional view taken generally along the line 5—5 of FIGURE 3;

FIGURE 6 is a view in end elevation, taken generally in the direction of the arrows 6—6 of FIGURE 5 and showing a portion of a frame side member and, by broken lines, the driving arrangement for the feed and retard shafts with the extension of the short shaft which is constantly driven being shown in section; and

2

FIGURE 7 is a sectional view taken generally along the line 7—7 of FIGURE 3.

Referring now particularly to FIGURE 1 of the drawings, it will be observed that the reference character 10 designates, generally, a feeder for documents, such as checks, of the general type shown in U.S. Patent No. 2,652,248, issued September 15, 1953. The feeder 10 is intended for feeding the documents to recording apparatus, such as microfilm recording apparatus, and for this purpose it is desirable that the documents be fed one by one in order that matter appearing on both sides can be recorded in a manner well understood.

The feeder 10 includes vertically disposed frame side members 11 and 12 which are positioned in parallel spaced relation and are interconnected, as shown in FIGURE 3, by frame transverse members 13, 14 and 15 in the form of bars having a square cross section. Screws 16, extending through the frame side members 11 and 12 into the ends of the frame transverse members 13, 14 and 15 serve to hold the assembly together and to provide a rigid frame work on which the apparatus to be described is mounted. At one end of the frame thus provided is a transverse plate 17 which is secured in position by screws 18 that extend into the frame transverse members 13. Disposed between the frame side members 11 and 12 and suitably secured thereto is a document support plate which is inclined, as shown in FIGURE 3, and is arranged to receive a stack of documents, such as checks, to be referred to presently. Positioned on the documents support plate 19 are guides 22 having curved upper ends 23 which overlie similarly curved upper end portion 24 of the document support plate 19. The guides 22 have upstanding walls 25 for receiving therebetween the stack of documents 26, such as a stack of checks, which are to be photographed on opposite sides. The guides 22 are adjustable on the document support plate 19 in order to accommodate different sizes of documents 26.

The documents 26 move downwardly along the inclined document support plate 19 underneath a lower curved portion 27 of a baffle 28 which extends between the frame side members 11 and 12 and is secured by screws 29 to the frame transverse member 14. The lower curved portion 27 has a slot 32 therein through which feed belts 33 carried by pulleys 34 project. The feed belts 33 are circular in cross section and are formed of material such as rubber or rubber like material which have good frictional gripping engagement with the uppermost of the documents 26 for feeding the same downwardly along the document support plate 19.

FIGURES 7 shows more clearly the mounting of the pulleys 34. It will be observed that they are formed integrally with sleeve portions 35 having bushings 36 at their ends for rotatable mounting on a shaft 37 which is carried at the ends of arms 38 which are provided with bushings 39 for journaling on a feed roller shaft 40. It will be understood that the arms 38 can rock about the axis of rotation of the feed roller shaft 40 accompanied by bodily movement of pulleys 34 together with those portions of the feed belts 33 therearound. As shown in FIGURE 5 the feed roller shaft 40 is journaled in bearing blocks 41 which are secured by screws 42 to the frame transverse member 14. A ring 43, secured by set screw 44 to the feed roller shaft 40, holds the latter against endwise movement in one direction.

As shown in FIGURE 7 a friction feed roller, illustrated generally at 46, is non-rotatably mounted on the feed roller shaft 40. The friction feed roller 46 includes integrally formed hubs 47 through which set screws 48 project to secure the feed roller 46 non-rotatably to the feed roller shaft 40. Reduced diameter central sections 49 are formed on the feed roller 46 around which the rub-

ber feed belts 33 extend and whereby they are driven on rotation of the feed roller 46.

The feed roller 46 also includes a large diameter central section 50 and large diameter end sections 51 all having a document engaging surface 52 which has a relatively high coefficient of friction. For example, the coefficient of friction of the document engaging surface 52 of the friction feed roller 46 may be of the order of 1.0, the surface being formed of a rubber like plastic material such as Plastosol.

It is desirable to provide for controlling the rotation of the friction feed roller 46. For this purpose an electromagnetically controlled clutch, shown generally at 54, is employed and it is positioned, as shown in FIGURE 5, to control the driving connection between the feed roller shaft 40 and a driving member, shown generally at 55, in the form of a gear 56. As will appear hereinafter provision is made for continuously driving the gear 56.

Formed integrally with the gear 56 is a sleeve 57 which is journaled in the frame side member 11 and within which are bushings 58 in which the reduced diameter end portion 59 of the feed roller shaft 40 is journaled. Surrounding the reduced diameter portion 59 is a sleeve 60 which is secured by a set screw 61 non-rotatably to the feed roller shaft 40. The external diameter of the sleeve 60 is the same as the external diameter of the sleeve 57 so that the surface of one is substantially an extension of the surface of the other. A helical clutch spring 62 surrounds the sleeve 57 and the sleeve 60 and is so arranged that the convolutions thereof lightly grip the surfaces of these sleeves. When the gear 56 is driven in the proper direction, the convolutions of the helical clutch spring 62 more tightly grip the surfaces of the sleeves 57 and 60 and drive the feed roller shaft 40 in the direction by the arrow 63 to effect corresponding rotation of the friction feed roller 46.

Provision is made for controlling the gripping action of the helical clutch spring 62. For this purpose one end 64 of the spring 62 extends into an armature 65 in the form of an annular magnetic member which is rotatably mounted on the sleeve 57 and is slidable endwise with respect thereto through a limited extent. Cooperating with the armature 65 is a coil 66 which may be connected by conductors 67 and 68 to a suitable current source, such as a direct current source. The connection is made through a normally open switch 69 which is interposed in the conductor 68. As will appear hereinafter provision is made for controlling the operation of the switch 69 to effect closure thereof and energization of the coil 66 when it is desired to interrupt the driving connection between the feed roller shaft 40 and the driving member 55. The magnetic circuit around the coil 66 includes a cylindrical core 70, an annular end plate 71 and a cylindrical housing 72 which is provided with a radial flange 73, FIGURE 2, that overlies a spacer 74 of non-magnetic material. Screws 75 extend through the flange 73 and spacer 74 to mount the cylindrical housing 72 and parts associated therewith on the frame side member 11.

With a view to accelerating the disengaging action of the helical clutch spring from the sleeves 57 and 60, the other end 76 of the spring 62 extends into a flywheel 77 which is rotatable on the sleeve 60. The inertia of the flywheel 77 is effective to release the gripping engagement between the convolutions of the helical clutch spring 62 on energization of the coil 66 in the manner described in more detail in copending application Serial No. 689,862, filed October 14, 1957, now abandoned, and assigned to the assignee on this application.

Cooperating with the friction feed roller 46, as shown more clearly in FIGURE 5 of the drawings, is a retard roller 80. The retard roller 80 is arranged to rotate in the same direction as the direction in which the feed roller 46 rotates for the purpose of permitting the documents 26 to be fed singly by the feed roller 46.

The retard roller 80 is provided with hubs 81 formed integrally therewith through which set screws 82 extend for non-rotatably securing the retard roller 80 to a retard shaft 83. The retard shaft 83 extends transversely through slots 84 in cylindrical bearing supports 85 which have integral flanges 86 that are secured by screws 87 to a bearing support plate 88. As shown in FIGURE 3, the bearing support plate 88 is secured by screws 89 to a transverse shaft 90 which may have a square cross section. The transverse shaft 90 is rockably mounted between the frame side members 11 and 12 by means of pivot screws 91, FIGURE 4, which have cylindrical bearing portions 92 that are journaled in suitable openings in the frame side members 11. The manner in which the bearing support plate 88 is controlled for positioning the retard roller 80 with respect to the feed roller 46 will be described hereinafter.

Referring again to FIGURE 5 of the drawings it will be observed that intermediate sections 93 of the retard roller 80 are positioned opposite the large diameter end sections 51 of the friction feed roller 46. In addition outboard sections 94 are formed integrally with the retard roller 80. It will be observed that an aperture 95 is provided in the bearing support plate 88 through which the sections 93 and 94 of the retard roller 80 project. Apertures 96 and 97 are provided in the document support plate 19 for receiving therethrough the sections 93 and 94 of the retard roller 80. The surfaces 99 of the sections 93 and 94 of the retard roller 80 have a relatively low coefficient of friction as compared to the coefficient of friction of the surface 52 of the friction feed roller 46. For example the coefficient of friction of the surface 99 may be of the order 0.707 and may be formed by suitable rubber like material having such a coefficient of friction such as Plastosol or polyvinyl chloride. The reason for employing materials having different coefficients of friction is set forth in detail in copending application Serial No. 700,171, filed December 2, 1957, and assigned to the assignee of this application.

It is desirable to maintain the spacing shown at 102 in FIGURE 5 between the document engaging surfaces 52 and 99 of the feed roller 46 and retard roller 80 even though these surfaces may wear from continued use. One manner of accomplishing this is disclosed in more detail in the copending application just referred to. Such means include bearings 103 that are slidably mounted in the cylindrical bearing supports 85 in which the retard shaft 83 is journaled. Coil compression springs 104 react between the bearings 103 and screw caps 105 that are threaded into the cylindrical bearing supports 85. The springs 104 bias the retard shaft 83 and thereby the retard roller 80 toward the feed roller 46. The springs 104 also bias the retard shaft 83 against wear shoes 106 that are circular in cross section and are shaped to bear against the retard shaft 83 for a limited arcuate extent. The wear shoes 106 project through openings 107 in the bearings 103 and are provided with threaded extensions 108 that are screwed into base portions 109 of the cylindrical bearing supports 85. The wear shoes 106 are so characterized that they wear away at a rate corresponding to the rate at which the surfaces 52 and 99 of the feed roller 46 and retard roller 80 wear away. As this wear takes place and the wear shoes 106 are reduced in thickness the spacing 102 remains constant.

It will be recalled that the retard roller 80 is rotated in the same direction as the direction, indicated by the arrow 63, in which the feed roller 46 is rotated. Specifically provision is made for rotating the retard shaft 83 in the direction indicated by the arrow 110 through the agency of a flexible shaft 111 which is connected to a short shaft 112 that is journaled in bearing bushings 113 that are carried by a sleeve 114 which is threaded in the frame side member 11. It will be observed that the short shaft 112 is rotatable about an axis that is fixed

in space while the retard shaft 83 is rotatable about an axis which is movable relative to the fixed axis of rotation of the short shaft 112. The retard shaft 83 is movable not only as the result of movement of the bearing support plate 88 but also its axis of rotation shifts slightly as the wear shoes 106 wear and the retard shaft 80 is moved toward the feed roller shaft 40 under the influence of the springs 104.

As shown in FIGURE 5 the short shaft 112 is provided with an extension 115 that projects beyond the frame side member 11 and is connected to suitable driving mechanism, such as the drive mechanism for the microfilm recorder, for rotating it constantly in the direction indicated by the arrow 110 while the mechanism is in operation.

FIGURE 6 shows the driving connection between the extension 115 and the feed roller shaft 40. It will be observed that a gear 116 is fast on the extension 115 and that it meshes with an idler gear 117 which is journaled at 118 on the frame side member 11. It will be observed that the idler gear 117 meshes with the gear 56 and that these gears are located in a triangularly shaped recess 119 which is formed in the outer side of the frame side member 11. A cover plate 120 overlies the recess 119 and parts disposed therein and is secured by screws 121 to the frame side member 11.

Referring now to FIGURE 3 of the drawings it will be observed that the bearing support plate 88 has an integrally formed extension 124 which also is shown in FIGURE 4. The sides of the extension 124 are inclined from the support plate 88 toward a bifurcated end 125 having a slot 126 in which a threaded stud 127 that stands upwardly from the frame transverse member 13 extends. The position of the bifurcated end 125 of the extension 124 can be varied by a thumb nut 128 which is threaded on the stud 127. A coil compression spring 129 reacts between the underside of a thumb nut 130, also threaded on the stud 127, and the upper side of the bifurcated end 125. By adjusting the thumb nut 130, the tension applied by the spring 129 to the extension 124 can be varied for varying the pressure that is applied by the retard roller 80 in the direction of the feed roller 46 and against the document or documents that may appear therebetween. A holding spring 131 is interposed between lock nuts 132, threaded on the stud 127, and the thumb nut 130 for maintaining it in any position to which it may be adjusted.

The presence of two or more documents or of a document of unusual thickness appearing between the feed roller 46 and retard roller 80 is detected by a sensing roller 135, FIGURES 3 and 4, which is journaled on a shaft 136 that extends between arms 137 of a sensing lever 138. The sensing lever 138 is rockably mounted on a shaft 139 which is journaled in bearing brackets 140 which are secured by screws 141 to the frame transverse member 15. A torsion spring 142 reacts against the sensing lever 138 to bias it in the direction indicated by the arrow 143, FIGURE 3, to cause the sensing roller 135 to engage the large diameter central section 50 of the friction feed roller 46. The sensing lever 138 has a channel shaped extension 144, FIGURES 3 and 5, and at its outer end there is a flat portion 145 which engages a plunger 146 of the normally open switch 69. The switch 69 includes a spring 147 which normally biases the plunger 146 to close the switch contacts. They are held open against the biasing action of the spring 147 by the flat portion 145 of the sensing lever 138 which is held in position by the torsion spring 142. The spring 147 which biases the plunger 146 is illustrated diagrammatically in FIGURE 5. The flat portion 145 of the sensing lever 138 continues to an offset portion 148 which extends through an aperture 149 in the transverse plate 17. By manually depressing the offset portion 148 of the sensing lever 138 in the direction indicated by the arrow 150, the plunger 146 of the switch 69 is relieved

and the spring 147 is free to close the contacts of the switch 69 for energizing the coil 66 to disconnect the driving connection between the driving member 55 and the feed shaft 40 for stopping further feeding of the documents by the feed roller 46. Since the retard roller 80 continues to rotate when the feed roller 46 is stopped, the document or documents therebetween are regurgitated. With a view to permitting adjustment of the position of the switch 69, FIGURE 3, it is mounted on an arm 152 which is rockably mounted on a shaft 153 that is carried by a bracket 154. The bracket 154 extends forwardly and upwardly from the frame transverse member 13 and is secured thereto by screws 155. The arm 152 has a rearward extension 156 which overlies a thumb nut 157 that is threaded on the stud 127. By varying the position of the thumb nut 157, a corresponding change is effected in the position of the arm 152 and thereby of the switch 69. A handle 159 extends rearwardly from the extension 156 and it is biased downwardly by a spring 160 that surrounds the stud 127 and is located underneath the thumb nut 128.

When it is desired to feed a document or documents having a thickness greater than normal, the operator can manually grasp the handle 159 and apply an upward force thereto as indicated by the arrow 161 to prevent closure of the contacts of the switch 69 by the downward swinging movement of the sensing lever 138 in response to movement of the sensing roller 135 as the result of the insertion between it and the feed roller 46 of the abnormal documents thickness.

In operation, provision is made for constantly rotating the extension 115 of the short shaft 112 and thereby causing rotation of the retard roller 80 in the direction indicated by the arrow 162 on FIGURE 3 of the drawings. At the same time, since the coil 66 of the electromagnetic clutch 54 is deenergized, the feed roller shaft 40 rotates to drive the feed roller 46 in the direction indicated by the arrow 163, FIGURE 3. The documents 26 are fed singly by the feed roller 46 and they pass between it and the sensing roller 135. As long as the document thickness does not exceed that for which the mechanism is set, the documents 26 continue to be fed one by one to the microfilm recording apparatus or other apparatus as the case may be.

Should a document having an extra thickness or two documents be fed between the feed roller 46 and the sensing roller 135, the latter is moved further away from the former and the sensing lever 138 is rocked in a counterclockwise direction against the biasing action of the torsion spring 142. The plunger 146 then moves downwardly under the influence of the spring 147, FIGURE 5, and contacts of the switch 69 are closed. Coil 66 is energized and, in the manner hereinbefore described, the clutch spring 62 is caused to release its gripping engagement with the sleeves 57 and 60. The feed roller shaft 40 and feed roller 46 promptly stop. Since the retard roller 80 continues to rotate in the direction indicated by the arrow 162, FIGURE 3, the document or documents are regurgitated and the sensing roller 135 is again biased toward the feed roller 46. The contacts of the switch 69 are opened and coil 66 is deenergized. Thereupon the clutch 54 is operated to restore the driving connection between the driving member 55 and the feed roller shaft 40 and the operation resumed.

Should it be desired to regurgitate the document or documents manually, the offset portion 148 of the sensing lever 138 is depressed in the direction indicated by the arrow 150 and the sequence of operation just described is effected to stop the feed roller 46 and permit the retard roller 80 to regurgitate the document or documents.

Since certain further changes can be made in the foregoing construction and different embodiments of the invention can be made without departing from the spirit and scope thereof, it is intended that all matter shown in

the accompanying drawings and described hereinbefore shall be interpreted as illustrative and not in a limiting sense.

What is claimed as new is:

1. In a document feeding mechanism, in combination, a rotatable feed roller having a document engaging surface positioned to continuously engage and frictionally feed documents from a stack to recording apparatus, a retard roller in opposed relation to said feed roller and rotatable continuously in the same direction as said feed roller and having a document engaging surface to continuously engage and cause said documents to be fed singly by said feed roller, driving means for said feed and retard rollers, normally engaged clutch means between said driving means and said feed roller for controlling the driving connection therebetween, and means for disengaging said clutch means to stop said feed roller and permit regurgitation of said documents by said retard roller.

2. In a document feeding mechanism, in combination, a rotatable feed roller having a document engaging surface positioned to continuously engage and frictionally feed documents from a stack to recording apparatus, a retard roller in opposed relation to said feed roller and rotatable in the same direction as that of said feed roller and having a document engaging surface to continuously engage and cause said documents to be fed singly by said feed roller, driving means normally operable to rotate said feed and retard rollers in the same direction, normally engaged clutch means between said driving means and said feed roller for controlling the driving connection therebetween, and means responsive to the feeding of two or more documents by said feed roller for disengaging said clutch means to stop said feed roller and permit regurgitation of said documents by said retard roller.

3. In a document feeding mechanism in combination, a cylindrical feed roller rotatable on the longitudinal axis thereof and having a document engaging surface positioned to continuously engage and frictionally feed documents from a stack to recording apparatus, a retard roller in opposed relation to said feed roller and rotatable in the same direction as that of said feed roller and having a document engaging surface to cause said documents to be fed singly by said feed roller, driving means normally operable to rotate said feed and retard rollers in the same direction, normally engaged clutch means between said driving means and said feed roller for controlling the driving connection therebetween, a sensing roller biased toward said feed roller for receiving documents therebetween, and means responsive to predetermined movement of said sensing roller away from said feed roller in response to appearance therebetween of two or more documents for disengaging said clutch means to stop said feed roller and permit regurgitation of said documents by said retard roller.

4. In a document feeding mechanism, in combination, a rotatable feed roller having a document engaging surface positioned to continuously engage and frictionally feed documents from a stack to recording apparatus, a retard roller in opposed relation to said feed roller and rotatable in the same direction as said feed roller and having a document engaging surface to continuously engage and cause said documents to be fed singly by said feed roller, driving means for said feed and retard rollers, normally engaged clutch means between said driving means and said feed roller for controlling the driving connection therebetween, electromagnetic means when energized disengaging said clutch means, a sensing roller in operative relation to said feed roller for receiving documents therebetween, a sensing lever carrying said sensing roller, means rockably mounting said sensing lever and biasing the same and thereby said sensing roller toward said feed roller, switch means connected to said electromagnetic means and controlled by said sensing lever

5 whereby it is responsive to predetermined movement of said sensing roller away from said feed roller in response to appearance therebetween of two or more documents for deenergizing said electromagnetic means and disengaging said clutch means to stop said feed roller and permit regurgitation of said documents by said retard roller.

10 5. In a document feeding mechanism, in combination, a rotatable feed roller having a document engaging surface positioned to continuously engage and frictionally feed documents from a stack to recording apparatus, a retard roller in opposed relation to said feed roller and rotatable in the same direction as said feed roller and having a document engaging surface to continuously engage and cause said documents to be fed singly by said feed roller, driving means for said feed roller, normally engaged clutch means between said driving means and said feed roller for controlling the driving connection therebetween, electromagnetic means when energized disengaging said clutch means, a sensing roller in operative relation to said feed roller for receiving the documents 15 therebetween, a sensing lever carrying said sensing roller, means rockably mounting said sensing lever and biasing the same and thereby said sensing roller toward said feed roller, switch means connected to said electromagnetic means and controlled by said sensing lever whereby it is responsive to predetermined movement of said sensing roller away from said feed roller for deenergizing said electromagnetic means and disengaging said clutch means, means rockably mounting said switch means in operative relation to said sensing lever, and means for adjusting 20 the position of said switch mounting means to vary the document thickness that can be accommodated between said feed and sensing rollers without effecting switch operation to stop said feed roller.

25 6. In a document feeding mechanism, in combination, a rotatable feed roller having a document engaging surface positioned to continuously engage and frictionally feed documents from a stack to recording apparatus, a retard roller in opposed relation to said feed roller and rotatable in the same direction as said feed roller and having a document engaging surface to continuously engage and cause said documents to be fed singly by said feed roller, driving means for said feed roller, normally engaged clutch means between said driving means and said feed roller for controlling the driving connection 30 therebetween, electromagnetic means when energized disengaging said clutch means, a sensing roller in operative relation to said feed roller for receiving the documents therebetween, a sensing lever carrying said sensing roller, means rockably mounting said sensing lever and biasing the same and thereby said sensing roller toward said feed roller, switch means connected to said electromagnetic means and controlled by said sensing lever whereby it is responsive to predetermined movement of said sensing roller away from said feed roller for deenergizing said electromagnetic means and disengaging said clutch means, means rockably mounting said switch means in operative relation to said sensing lever, and manually operable means connected to said switch mounting means for rendering said switch means inoperative to deenergize 35 said electromagnetic means and permit the feeding of documents having a greater than normal thickness.

40 7. In a document feeding mechanism, in combination, a rotatable feed roller having a document engaging surface positioned to frictionally feed documents from a stack to recording apparatus, a retard roller in opposed relation to said feed roller and rotatable in the same direction as said feed roller and having a document engaging surface to cause said documents to be fed singly by said feed roller, a retard shaft carrying said retard 45 roller and rotatable therewith, a support plate on which

said retard shaft is journaled, means rockably mounting said support plate about an axis offset from and parallel to the axis of rotation of said retard shaft, means biasing said support plate and thereby said retard roller toward said feed roller, driving means for said feed roller, normally engaged clutch means between said driving means and said feed roller for controlling the driving connection therebetween, a short shaft journaled to rotate about an axis fixed in space relative to said axis of rotation of said retard shaft and disposed in general endwise relation with respect thereto, a flexible shaft interconnecting said retard shaft and said short shaft, means for driving said short shaft, a sensing roller biased toward said feed roller for receiving documents therebetween, and means responsive to predetermined movement of said sensing roller away from said feed roller in response to appearance therebetween of two or more documents for disengaging said clutch means to stop said feed roller and permit regurgitation of said documents by said retard roller.

8. In a document feeding mechanism, in combination, a rotatable feed roller having a document engaging surface positioned to frictionally feed documents from a stack to recording apparatus, a retard roller in opposed relation to said feed roller and rotatable in the same direction as said feed roller and having a document engaging surface to cause said documents to be fed singly by said feed roller, a retard shaft carrying said retard roller and rotatable therewith, a support plate on which said retard shaft is journaled, means rockably mounting said support plate about an axis offset from and parallel to the axis of rotation of said retard shaft, means biasing said support plate and thereby said retard roller toward said feed roller, means for adjusting said biasing means to vary the pressure applied by said retard roller in the direction of said feed roller, driving means for said feed roller, normally engaged clutch means between said driving means and said feed roller for controlling the driving connection therebetween, a short shaft journaled to rotate about an axis fixed in space relative to said axis of rotation of said retard shaft and disposed in general endwise relation with respect thereto, a flexible shaft interconnecting said retard shaft and said short shaft, means for driving said short shaft, a sensing roller biased toward said feed roller for receiving documents therebetween, and means responsive to predetermined movement of said sensing roller away from said feed roller in response to appearance therebetween of two or more documents for disengaging said clutch means to stop said feed roller and permit regurgitation of said documents by said retard roller.

9. In a document feeding mechanism, a cylindrical feed roller mounted rotatably on a predetermined axis, at the center thereof, a retard roller, means urging the retard roller toward the feed roller into continuous engagement with a sheet and hold the sheet against the feed roller and permitting movement of the retard roller away from the feed roller, a justable stop means limiting movement of the retard roller toward the feed roller, means for rotating the feed roller in a direction such as to advance the sheet between the rollers, means for continuously rotating the retard roller in a direction tending to advance the sheet from between the rollers, and means responsive to feed of more than one sheet for stopping the feed roller rotating means.
10. In a document feeding mechanism, means for supporting a stack of documents, feed means continuously engaging the top document, first drive means driving the feed means so as to feed the top document in a forward direction, retard roller means mounted rotatably in a position opposed to the feed means for continuously engaging the document, second drive means driving the retard roller means continuously in a direction tending to prevent documents below the top document from being advanced with the top document, means urging the retard roller means toward the feed means, means limiting movement of the retard roller means toward the feed means, and means responsive to the presence of more than one document between the feed means and the retard roller means for rendering the first drive means inoperative.
11. In a document feeding mechanism, forward feed means for continuously engaging a document and feeding the document forwardly, retard feed means in opposed relationship with the forward feed means for continuously engaging and feeding a document rearwardly, sensing means for detecting the presence of more than one document between the forward feed means and the retard feed means and responsive thereto for rendering the forward feed means inoperative, and selectively operable means for rendering the sensing means operative and inoperative.
